(57) **CLAIM**

The ornamental design for a can cover, as shown and described.

DESCRIPTION

FIG. 1 is a bottom view of a can cover, showing my new design.

FIG. 2 is a side elevation view of the can cover of FIG. 1.

FIG. 3 is a top view of the can cover of FIG. 1.

FIG. 4 is a bottom perspective view of the can cover of FIG. 1.

FIG. 5 is a top perspective view of the can cover of FIG. 1.

FIG. 6 is a bottom view of the can cover of FIG. 1, shown in an alternate environment;

FIG. 7 is a side elevation view of the can cover of FIG. 6.

FIG. 8 is a top view of the can cover of FIG. 6.

FIG. 9 is a bottom perspective view of the can cover of FIG. 6.

FIG. 10 is a top perspective view of the can cover of FIG. 6.

FIG. 11 is a bottom view of the can cover of FIG. 1, shown in an alternate environment;

FIG. 12 is a side elevation view of the can cover of FIG. 11.

FIG. 13 is a top view of the can cover of FIG. 11.

FIG. 14 is a bottom perspective view of the can cover of FIG. 11; and,

FIG. 15 is a top perspective view of the can cover of FIG. 11.

In the drawings, the broken lines indicate environmental structure and form no part of the claimed design.
